UNITED STATES PATENT OFFICE.

WILLIS PIPPERT, OF RUMFORD, MAINE, ASSIGNOR TO CONTINENTAL PAPER BAG COMPANY, OF NEW YORK, N. Y., A CORPORATION OF MAINE.

FEEDING MECHANISM.

1,031,195.

Specification of Letters Patent.

Patented July 2, 1912.

Application filed October 6, 1911. Serial No. 653,199.

To all whom it may concern:

Be it known that I, WILLIS PIPPERT, a citizen of the United States, and a resident of Rumford, in the county of Oxford and State 5 of Maine, have invented certain new and useful Improvements in Feeding Mechanisms, of which the following is a specification.

This invention relates to feeding mechanism for paper bags particularly for self 10 opening square, satchel bottom or similar bags in which one end of the bottom thereof is folded onto the body thereof.

The object of my improvements is to furnish a mechanism of the class specified of 15 simple construction and rapid and reliable in operation.

Other objects will appear in the description following.

20 The accompanying drawings illustrate the preferred form of my improvements and Figure 1 is an assembled side elevation, with the front frame removed. Fig. 2 is a plan view corresponding with Fig. 1. Figs. 3 to 7 25 inclusive are fragmentary side views illustrating steps in the operation of my improved machine.

In the manufacture of paper bags it is often common practice and convenient to 30 fold the bag bottom onto the face or seamless side but if it is desired to print upon said face or seamless side after the bag is completed it is necessary to reverse the fold of the bag bottom relative to the body portion and turn the bottom onto the seam side, so as to present an entirely unbroken surface to print upon. To do this by hand is a 35 tedious and expensive operation and I have herein illustrated means for thus reversing 40 the bag bottom relative to the bag body in delivering the bag from a containing hopper to the cylinder of the printing press.

Rotating impression cylinder 3 is fixed to shaft 4 rotatively supported in side frames 45 5, 6. Said cylinder is provided with one or more sets of grippers as 7, 7 fixed to shaft 8 pivotally mounted in cavity 9 below the face of said cylinder. Said shaft 8 projects beyond the end of said cylinder and has gear 50 10 fixed thereto for engagement with gear 11 of segment 12 fixed to shaft 13 pivoted in the end of said cylinder. Said segment 12 has roll 14 pivotally fixed thereto between gear 11 and pivot 13, for engagement with 55 fixed cam 15 coaxial with cylinder 3. Shaft

13 has arm 16 fixed thereto and between the free end of said arm 16 and ear 17 on the end of said cylinder is compression spring 18. By these means said grippers 7, 7 may be actuated to close and open to successively 60 grip to said cylinder and release therefrom the underfolded end 40 of the paper bag bottom. Above said cylinder I have provided means for supporting a pile of bags 50 comprising forward lips 19, 19 and rearward lips 20, 20. Between said forward and rearward lips and extending crosswise said bags and parallel with the axis of cylinder 3 is turning bar 21 downwardly around which the bag body is drawn. Said turning bar is 65 rigidly supported at its ends by rods 38, 38 depending from brackets 39, 39 and said bar preferably has its rear edge 22 rounded so that the bag bodies will pass around it with ease. Said bar 21 also provides a center 70 support for the pile of bags. Adjustable side guides 23, 230 may be provided if desired.

While the normal tendency of the underfolded end 40 of the bag bottom 41 is to 80 spring away from said bag bottom downwardly toward the cylinder and into the path of grippers 7, 7, I find that greater certainty and precision of operation is had by bending said underfolded end 40 downwardly by positioning means. For this purpose I have provided a reciprocating poker 24 slidably mounted in mortise 25 in bar 21 and adapted to be moved rearwardly and preferably downwardly for bending said 85 underfolded bottom end 40 toward said cylinder 3. Said poker 24 has a wedge shaped end 26 for engaging the bag and the rearward end of said poker is slidably supported in bracket 27 upstanding from cross bar 28. 90 For reciprocating poker 24 cam 29 on shaft 30 engages roll 31 of arm 32 fixed to shaft 33. Arm 320 also fixed to shaft 33, is connected to poker 24 by link 34. Spring 35 on poker 24 is efficient to keep roll 31 in contact with cam 29. Shafts 30 and 4 are 95 geared together by equal gears 36, 37 respectively.

The operation of my improved mechanism is as follows: A pile of bags 50 having been 105 placed in position with the open ends of said bags on lips 19, and the closed or bottom ends on lips 20 and their mid portions on turning bar 21, the body portions of said bags tend to sag, causing the underfolded 110

portion 40 of the bottom bag to protrude slightly from body 41 thereof (Fig. 3). The machine being then started grippers 7, 7 begin to rotate outwardly from within pocket 9 in cylinder 3 and poker 24 moves rearwardly (to the right Fig. 4) its wedge shaped end 26 between bag body 41 and underfolded bottom portion 40, poking said underfolded portion downwardly in front of grippers 7, 7, (Fig. 4), without moving said bag body relative to the bag pile supporting means. Said grippers as they turn over toward their seats on cylinder 3 encounter the pile of bags and slightly lift that pile during the engagement of poker end 26 with bottom portion 40, thereby affording ample room between the bag body and bottom for the entrance of said grippers (Fig. 5). Poker 24 now commences to withdraw and cylinder 3 has advanced until edge 48 of cavity 9 has passed into approximate coincidence with the edge of bag-bottom portion 40. Thereupon, grippers 7, 7 descend and grip said portion 40 to cylinder 3 (Fig. 6). The bottom end of the bag is then withdrawn from lips 20 (Fig. 1) and the open end of body portion 41 is withdrawn from lips 19. That portion of body 41 near the jointure with the bottom is then folded backwardly onto bottom portion 42 and the main body portion is led downwardly around rounded edge 22 of turning bar 21 onto cylinder 3 ready for printing (Fig. 7) with its bottom side up, relative to its previous position on the pile supporting means.

I claim:—

1. Feeding mechanism for paper bags whose bottoms have one end thereof folded 40 backwardly onto their bodies respectively, including in combination means for supporting a pile of bags, a moving receiving member having bag-gripping means thereon, means for bending the backwardly 45 folded end of said bag-bottom downwardly into the path of the bag-gripping means and means for moving said receiving member toward the open end of the bag for withdrawing the bag from the pile supporting means and laying it on said moving member bottom side up relative to its previous position on the pile supporting means.

2. Feeding mechanism for paper bags whose bottoms have one end thereof folded 55 onto their bodies respectively, including in combination means for supporting a pile of bags, a moving receiving member having bag-gripping means thereon, means for bending the folded end of said bag-bottom 60 downwardly into the path of the bag-gripping means, means for actuating the bag-gripping means to grip said downwardly bent bag-bottom end to said receiving member, a turning bar for the bag-body and 65 means for moving said receiving member to

draw said bag-body around said turning bar.

3. Feeding mechanism for paper bags whose bottoms have one end thereof underfolded relative to their bodies respectively, 70 including in combination means for supporting a pile of bags, a moving receiving member having bag-gripping means thereon, means for bending the underfolded end of said bag-bottom downwardly into the 75 path of the bag-gripping means, means for actuating the bag-gripping means to grip said downwardly bent bag-bottom end to said receiving member, a turning bar for the bag-body, means for moving said receiving member to draw said bag-body around said turning bar and for laying it on said moving member, bottom side up 80 relative to its previous position on the pile supporting means. 85

4. Feeding mechanism for paper bags whose bottoms have one end thereof folded backwardly onto their bodies respectively, 90 including in combination means for supporting a pile of bags, a rotating cylinder having a gripper thereon, means for bending the backwardly folded end of said bag-bottom downwardly into the path of the cylinder gripper, means for actuating said gripper to grip said downwardly bent bag-bottom end to said cylinder and means for rotating said cylinder toward the open end of said bag for withdrawing the bag from the pile supporting means and laying it on said moving member bottom up relative to 100 its previous position on the pile supporting means. 95

5. Feeding mechanism for paper bags whose bottoms have one end thereof folded onto their bodies respectively, including in 105 combination means for supporting a pile of bags, a rotating cylinder having a gripper thereon, means for bending the folded end of said bag-bottom downwardly into the path of the cylinder gripper, means for actuating said gripper to grip said downwardly bent bag-bottom end to said cylinder, a turning bar for the bag-body, means for rotating said cylinder for drawing said bag body around said turning bar and for 110 laying it on said cylinder, bottom side up relative to its previous position on the pile supporting means. 115

6. Feeding mechanism for paper bags whose bottoms have one end thereof folded 120 backwardly onto their bodies respectively, including in combination means for supporting a pile of bags, a moving receiving member having bag-gripping means thereon, a reciprocating poker for bending downwardly into the path of the bag-gripping means the backwardly folded end of said bag-bottom, means for actuating said poker and means for moving said receiving member toward the open end of the bag for 125 130

- withdrawing the bag from the pile supporting means and laying it on said moving member bottom side up relative to its previous position on the pile supporting means.
- 5 7. Feeding mechanism for paper bags whose bottoms have one end thereof folded onto their bodies respectively including in combination, means for supporting a pile of bags, a moving receiving member having 10 bag-gripping means thereon, means for actuating said bag-gripping means, a turning bar for the bag-body and means for moving said receiving member to draw said bag-body around said turning bar.
- 15 8. Feeding mechanism for paper bags whose bottoms have one end thereof folded backwardly onto their bodies respectively, means for supporting a pile of bags, a moving receiving member having bag gripping 20 means thereon, means for bending the backwardly folded end of said bag-bottom downwardly into the path of the bag-gripping means without moving the bag-body relative to the bag pile supporting means and means for moving said receiving member toward the open end of the bag for withdrawing the bag from the pile supporting means and laying it on said moving member bottom side up relative to its previous position on the pile supporting means. 25
- Signed at Rumford, Maine, this 29 day of September, 1911, before two subscribing witnesses.
